UNITED STATES PATENT OFFICE.

FRANK BODY, OF TORONTO, ONTARIO, CANADA.

VALVE-SPRING LIFTER.

Application filed March 2, 1927. Serial No. 172,130.

My invention relates to improvements in valve spring lifters, and the object of the invention is to devise a simple device by which a maximum power can be exerted in lifting the spring and in which the operating lever is readily controllable by the operating hand to lock or unlock as desired, and it consists essentially of the arrangement and construction of parts as hereinafter more particularly explained.

Fig. 1 is a side elevation of my device showing it applied to a valve and valve spring, showing the parts of the lifter in the initial position.

Fig. 2 is a similar view to Figure 1 showing the parts in the position they assume when the spring is lifted.

Fig. 3 is a sectional plan view through my device separated from the valve and taken on line 3—3 Figure 1.

In the drawing like characters of reference indicate corresponding parts in each figure.

1 indicates a valve, 2 the stem, and 3 the spring abutting at one end against the engine body and at the opposite end against the usual cross pin 4.

In order to lift the spring 3 to remove the cross pin 4 I provide the following device.

The main frame of the device comprises a vertical portion 5 having a horizontally extending portion 6 at its upper end and a downwardly inclined portion 7 at its lower end. The vertical portion of the frame is provided with a ratchet rack 8.

9 is an operating lever which is preferably formed of band iron bent to form a double arm, the members 9^a and 9^b of which extend at each side of the inclined portion 7 of the frame. The lever 9 is pivoted at the end of the portion 7 by a cross pin 9^c.

10 is a locking dog, the upper end of which engages the ratchet 8 and the lower end is formed into a V-shaped portion providing an upwardly extending arm 10^a forming a thumb piece by which the upper end of the dog may be thrown in and out of engagement with the ratchet rack 8. Between the dog 10 and the vertical portion

5 of the frame is located a tension spring 11 secured at one end to the dog 10 as indicated at 11^a and at the opposite end to the operating lever as indicated at 11^b.

12 is a fork which is channel shaped in cross section so as to fit around the end of the operating lever, and is secured thereto

by means of a pivot pin 13. 14 is a screw spindle which extends through a threaded orifice 15 formed in the outer end of the arm 6, the lower end of the spindle bearing 60 against the upper face of the valve 1 when the device is in operation.

In operating my device the lower end of the spindle 14 is placed upon the centre of the valve head 1 and the fork 12 passed 65 beneath the lower end of the spring 3 so that the valve spindle 2 enters the crotch of the fork, the crotch being so formed as to permit the cross pin 4 passing therethrough. The angle of the frame formed by the vertical portion 5 and horizontal portion 6 is gripped in one hand of the operator and downward pressure is then brought to bear upon the outer end of the operating lever 9, thereby forcing the valve spring upward 70 75 into compressed position away from the cross pin 4.

When in this position the engaging end of the dog 10 enters one of the lower teeth of the ratchet 8 thereby holding the spring 80 3 in locked position. The cross pin 4 may then be removed. When the cross pin 4 is removed the operator again grips the operating lever and depresses the thumb piece 10^a with his thumb thereby disengaging the 85 dog 10 from the ratchet 8. Manual pressure on the lever 9 may then be gradually relieved to permit the spring to expand. When the spring is fully expanded the 90 spring lifter may then be removed and the spring removed from the valve spindle.

What I claim as my invention is:—

A valve spring lifter comprising a frame formed by a vertical bar portion having a horizontal portion at its upper end and an 95 inwardly extending portion at its lower end a double armed lever pivoted to the frame and between the arms of which the inwardly extending portion of the frame extends, a pivot pin extending through the arms of 100 the lever and through such inwardly extending portion, a fork member pivoted to the inner end of the lever, a dog pivoted between the arms of the lever adjacent the operating end and having a V-shaped lower 105 end forming an upwardly inclined thumb piece, a ratchet rack formed in the vertical portion of the frame, and a tension spring connected at one end to the engaging portion of the dog and at the opposite end between the arms of the operating lever. 110
